UNITED STATES PATENT OFFICE.

DANIEL H. TWAITS, OF CHICAGO, ILLINOIS.

GREASE-CUP CAP.

1,200,904.

Specification of Letters Patent.

Patented Oct. 10, 1916.

Application filed January 26, 1914. Serial No. 814,316.

To all whom it may concern:

Be it known that I, DANIEL H. TWAITS, a citizen of the United States, residing at Chicago, in the county of Cook and State of Illinois, have invented a certain new and useful Improvement in Grease-Cup Caps, of which the following is a full, clear, and exact description, reference being had to the accompanying drawings.

10 This invention relates to grease cups of a type wherein there are two members, one of which screws onto the other, and a spring detent is provided for preventing one of the members rotating with relation to the 15 other and thereby becoming inadvertently removed therefrom.

The object of the invention is to provide an efficient detent spring device adapted to be readily secured to one of the members of 20 the cup and which shall be durable in service and cheap to manufacture.

My invention is hereinafter more fully described and the essential characteristics set forth in the claims.

25 In the drawings, Figure 1 is a central vertical section through the grease cup showing my spring device mounted therein; Fig. 2 is a central vertical section through the grease cup showing the modified construction of my spring device; Fig. 3 is a central vertical section taken on a plane at right angles to Fig. 2; Fig. 4 is a horizontal section taken on the line 4—4 of Fig. 2; Fig. 5 is a detail of the spring shown in Fig. 1 before being bent and attached to the cup; Fig. 6 is a detail of the form of spring device shown in Figs. 2 to 4 before such spring is bent into position.

30 In the drawings, 10 indicates a grease cup body having an enlarged portion 11 forming a head, which is provided with external threads adapted to coöperate with the internal threads 12 of the cap member 14. The cap 14 is open at its lower end to allow 40 for screwing it into position and is provided with a flat top 15 closing the upper end. The interior of the body 10 may be provided with vertical grooves, or may be angular, as shown at 16, thus providing corners or grooves for engaging the detent spring device 17 to prevent the cap inadvertently turning on the body portion, thereby becoming displaced or lost.

45 In the form shown in Figs. 1 and 5, the 50 spring device consists of a flat strip secured at its two ends to the top of the cap,

as shown at 18, and having two downwardly extending legs 20 bent outwardly at 21 and then in toward the center and upwardly at the connecting portion 22 forming two loops 60 connected by the intermediate portion. On the outer portion of the loops 21 are formed projections 24 adapted to engage the corners or vertical grooves in the body portion to prevent the cap turning, except when considerable force is used, such as firmly grasping the cap by the hand to turn the same. When so turned, the loops and projections 65 24 spring toward each other past the flat or narrow portion of the interior of the base, 70 and expand again into the corners or wider portions of the interior. The legs 20 and the connecting portion 22 tend to spring outwardly providing the desired yielding engagement with the interior of the base. The 75 upper ends of the legs 20 may be secured to the cap in any suitable manner. As shown in Fig. 1, they are turned outwardly and riveted thereto, but it is to be understood that I do not wish to be limited to this 80 method of securing the spring to the cap, as these portions might be electrically welded to the top of the cap or may have upwardly extending lugs extending through the cap and upset at their upper ends, as shown at 85 26 in Figs. 2 and 3.

85 Figs. 2, 3, 4 and 6 show a modified construction of the spring device in which the spring consists of two depending legs 30 and 31 bent outwardly at 32 and then inwardly, and having a sliding connection 33 between the two legs. On the outwardly bent portions 32 are provided projections 35 similar to the projections 24. In this form the legs 30 and 31 tend to spring outwardly by their own spring action, causing them to engage the base. When the cap is rotated causing the lower ends to move toward and away from each other, the horizontal portion 36 slides under the horizontal 90 end 39 of the leg 30. The spring is strengthened and these ends of the legs are prevented from lateral movement with relation to each other by means of ears or wings 40 integral with the portion 38, bent upwardly 95 and around the sides of the portion 39 providing a slidable engagement therewith. This construction allows the wings to spring toward and away from each other while preventing one leg being bent out of its normal relation with the other in case the lower end should become caught, or for any rea- 100 105 110 115

son should be held against turning, thereby tending to cause the spring to be bent or distorted by the turning of the cap. These springs are secured to the cap by the lugs 26 heretofore mentioned, which extend through suitable openings in the top thereof and are upset at the upper side of the top. The metal at the base of these lugs 26 may be spread outwardly, as shown at 42, to provide 10 a wider shoulder engaging the under side of the cap, thereby more rigidly holding each leg of the spring against moving with relation to the cap and working loose. By making such a spring device of flat strips of 15 metal, I provide for the same being readily punched from sheet metal, it being only necessary then to bend the spring to the desired form and secure it to the cap. This provides a very cheap method of manufacture, and the fact that the springs are flat 20 provides the greatest strength of the material where it is most needed. That is, the greatest strength, across the width of the spring members, resists the side strain on 25 each leg of the spring when the cap is rotated.

Having thus described my invention, what I claim is:

1. The combination of a grease cup comprising a cap member and a body member coöperating therewith, a spring detent device comprising two portions each secured at one end to one of the members and adapted to engage the other member at their 25 other ends, and means connecting the engaging ends allowing them to move toward and away from each other while preventing the distortion of the spring.

2. The combination of a grease cup comprising a cap member and a body portion, a spring detent device comprising two substantially parallel portions secured at their upper ends to the cap and having outward projections at their lower ends engaging the 45 interior of the body, and a connecting portion between the two lower ends allowing these ends to move toward and away from each other.

3. The combination of a grease cup comprising a cap member and a body member coöperating therewith said body member having vertical grooves on the interior and a spring detent device comprising two flat depending portions secured to the cap, the 55 flats of these depending portions being substantially parallel and having at their lower ends outwardly extending portions provided with projections engaging the interior of the body and having a connecting portion allowing these ends to move toward and away from each other while preventing the ends moving laterally with relation to each other.

4. In a grease cup, the combination of a 65 body portion having vertical grooves on the

interior and external threads, a cap member threaded to coöperate with said external threads, and a spring detent device comprising two substantially parallel legs secured at their upper ends to the cap and being bowed outwardly at their lower ends and provided with projections for engaging the interior of the body and having a connecting portion allowing the lower ends to spring toward and away from each other, 75 said spring device being so formed as to cause the lower ends of the legs to spring outwardly.

5. The combination of a grease cup comprising a cap member and a body member coöperating therewith, and a spring detent device having two substantially parallel portions secured to one of the members having means for engaging the other member of the grease cup and having inwardly turned portions at their lower ends, one of which slidably embraces the other.

6. The combination of a grease cup body comprising a body member and a cap member threaded thereto, and a spring detent device having two substantially parallel portions of flat spring metal each securely attached at one end to one of the cup members, means at their opposite ends for engaging the other cup member, and inwardly turned portions overlapping each other, one of said portions having wings bent around the other providing a slidably engagement therewith while preventing the distortion of the spring members.

7. The combination of a grease cup comprising a body member and a cap member threaded thereto, and a spring detent device comprising flat spring members having two substantially parallel portions, means on their upper ends for securing them to the cap member, said portions being bowed outwardly at their lower ends and then inwardly, said outwardly bowed portions being provided with projections engaging the interior of the body, and means connecting the inwardly bent portions allowing the bowed portions to move toward and away from each other, said spring device being so formed that the bowed portions tend to spring outwardly into engagement with the interior of the body.

8. The combination with a grease cup comprising a cap member and a body member coöperating therewith, of a spring detent comprising two portions secured to the cap and depending into the base and having a connecting means bracing one portion by the other while permitting them to spread outwardly.

9. The combination of a grease cup comprising a cap member and a body member, a spring detent device comprising a plurality of members secured at their upper ends to the cap and depending into the base and 130

having connecting means at their lower ends allowing them to be moved toward and away from each other, while bracing one by the other.

5 10. The combination of a grease cup comprising a cap member and a body member, a spring detent device comprising two depending members secured at their upper ends to the cap and having outward projections at their lower ends engaging the in-

terior of the body and having their lower ends turned inwardly with slidably engaging overlapping portions at these lower ends.

In testimony whereof, I hereunto affix my 15 signature in the presence of two witnesses.

DANIEL H. TWAITS.
